DRAG SAW

Filed May 10, 1924

3 Sheets-Sheet 3

UNITED STATES PATENT OFFICE.

KENNEY F. MILES, OF PORTLAND, OREGON.

DRAG SAW.

Application filed May 10, 1924. Serial No. 712,299.

To all whom it may concern:

Be it known that I, KENNEY F. MILES, a citizen of the United States, residing at Portland, in the county of Multnomah and State of Oregon, have invented certain new and useful Improvements in Drag Saws, of which the following is a specification, reference being had to the accompanying drawings.

10 This invention relates to certain improvements in drag saws and has relation more particularly to a device of this general character which is motor driven and it is an object of the invention to provide a device of this kind embodying novel and improved means whereby the same can be used for felling trees or as a bucking saw.

Another object of the invention is to provide a device of this general character comprising a support together with a saw carrying frame mounted thereon and adapted to be adjusted to different positions in accordance with the character of the work, said support and frame being provided with means to effect the requisite reciprocation of the saw.

The invention consists in the details of construction and in the combination and arrangement of the several parts of my improved drag saw whereby certain important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein—

Figure 1 is a view in top plan illustrating a drag saw operating mechanism constructed in accordance with an embodiment of my invention and arranged for cutting up a log;

45 Figure 2 is a detailed view partly in section and partly in elevation of the mechanism as herein disclosed, the line of section being substantially on the line 2—2 of Figure 1;

50 Figure 3 is a sectional view taken substantially on the line 3—3 of Figure 2;

Figure 4 is a fragmentary view in elevation illustrating certain features of the saw head as herein comprised;

55 Figure 5 is a view partly in longitudinal section and partly in elevation of the struc-

ture as illustrated in Figure 1 with the saw frame adjusted into position for felling a tree;

60 Figure 6 is an enlarged fragmentary sectional view taken substantially on the line 6—6 of Figure 5, arranged for operation in another position;

65 Figure 7 is a view partly in section and partly in elevation illustrating one of the interchangeable bearings as herein disclosed;

70 Figure 8 is a view in perspective of the members for coaction with the swinging frame to hold the same in position to effect an undercut when felling a tree;

75 Figure 9 is a view in end elevation of the interchangeable bearings unapplied;

75 Figure 10 is a view in perspective of a stand adapted to support one end of the mechanism when felling a tree;

80 Figure 11 is an enlarged fragmentary sectional view illustrating a means for holding the stand in its various adjustments;

80 Figure 12 is a fragmentary view in top plan illustrating the means whereby a chain may be employed for holding the device in position with respect to the work.

85 Figure 13 is a view in perspective of the mounting or stub shaft particularly disclosed in Figure 12;

85 Figure 14 is a fragmentary elevational view of one of the dogs adapted to engage the work when the saw is used for bucking;

90 Figure 15 is a view in top plan illustrating a mechanism constructed in accordance with a further embodiment of my invention.

95 As disclosed in the accompanying drawings S denotes a supporting structure comprising side members 1 arranged in parallelism and herein disclosed as each constituting an angle iron. The members 1 intermediate their ends are connected by the cross members 2, 3 and 4 also herein disclosed as angle irons and which maintain the side members 1 in predetermined spaced relation. The central portions of the members 2, 3 and 4 are provided with bearings 5 which rotatably support the shaft 6, said shaft 6 intermediate the members 2 and 3 being provided with the sprocket wheel 7 adapted to be operatively engaged with a suitable source of power whereby the shaft 6 may be driven.

100 Freely mounted on the shaft 6 between the members 3 and 4 and immediately adjacent to said members are the parallel arms 8 provided at their outer ends with the

bearings for the shaft 10. The shaft 10 is in parallelism with the shaft 6 and mounted on the central portion of said shaft 10 is an outstanding yoke 11, the central portion of which being provided with a bearing 12 arranged at right angles to the shaft 10.

Fixed to the shafts 6 and 10 are the sprocket wheels 14 around which are disposed the chain 15 whereby the shaft 10 is driven from the shaft 6. Fixed to the shaft 10 at a point within the yoke 11 is a gear 16 in mesh with the gear 17 carried by the inner end portion of a shaft 18 disposed through and rotatably supported by the bearing 12. This shaft 18 extends beyond the yoke 11 a desired length and has its outer end terminating in a crank 19 for a purpose to be hereinafter more particularly referred to.

Engaged with the opposite end portions of the shaft 10 and with the shaft 18 are the bearing members 20, said members being of similar construction but as herein disclosed each of said members 20 constituting a block provided in its opposite ends with the open slots 21 through which are adapted to be disposed the headed members 22 and with each of which members coacts in a well-known manner a quick acting nut 23.

Fixed to the outer end portion of the shaft 18 and in close proximity to the crank 19 is a pair of spaced collars 24 and fixed on said shaft 18 between the collars 24 is an eccentric 25. Disposed around the eccentric 25 are the straps 26, held in assembled relation by the nuts 27 coacting with the outer faces of the contacting lugs 28 carried by the extremities of the straps 26.

The nuts 27 are threaded upon the guide rods 29 of desired length and in sliding engagement with these rods 29 is a head H. The outer end portions of the rods 29 are connected by a cross member 30 having disposed therethrough a kerf 31 through which works the saw blade B. This blade B is operatively engaged with the head H for reciprocation therewith, the connection between the head H and blade B being preferably in the manner disclosed in my application for patent executed on the 25th day of April, 1924.

One end portion of the member 30 is provided with a hand grasp 32 whereby requisite pressure may be imposed upon the blade B during a working operation to facilitate the desired cutting action. The inner end portion of the head H at substantially its transverse center has operatively engaged therewith, as at 33, a pitman 34 also operatively engaged, as at 35, with a crank 19 so that upon rotation of the shaft 18 requisite reciprocation may be imparted to the head H and the saw blade B carried thereby.

The forward ends of the side members 1

are connected by the inwardly curved arcuate member 36 provided adjacent its opposite ends with the outstanding penetrating members or prongs 37. The side members 1 inwardly of their outer ends have secured thereto the plates 38 carrying the inwardly directed lugs 39 with which are freely engaged the inner end portions of the elongated dogs 40. One of the members 1 forwardly of the plate 38 carried thereby has fixed thereto the plate 41 adapted to be secured to a face of the member 1 remote from that to which the plate 38 is secured. The plate 41 is provided with a perpendicularly related elongated stub or arm 42 disposed through the adjacent flange of the member 1 and having its outer end portion terminating in a reduced extremity 43, the free end of which being provided with an outstanding radial lug 44. An elongated arm 45 is provided at one end portion of a hub 46 the bore of which having in communication therewith a radially disposed recess 47. The recess 47 provides means whereby the hub 46, when the arm 45 is in one position, is adapted to be engaged with the reduced portion 43 of the stub or arm 43, said lug 44 serving to hold the arm in applied position with respect to the stub or arm 42 when the arm 45 is swung to offset the recess 47 with respect to said lug 44.

The outer end portion of the arm 45 rotatably supports a block or pulley 48 of a conventional type and with which an end portion of a chain 49 is engaged, the opposite end portion of said chain 49 being secured, as at 50, to the forward end portion of the second side member 1. The pulley 48 carries a ratchet 51 with which engages a pawl 52 pivotally engaged with the arm 45 and which pawl 52 serves to hold the block or pulley 48 against rotation in one direction for a purpose to be hereinafter more particularly referred to.

The rear end portions of the side members 1 have secured thereto the plates or members 53 provided with the inwardly directed stubs or lugs 54 with which are pivotally engaged the extremities of a substantially V-shaped member 55, the apex portion of which being angularly disposed, said apex portion affording the straight member 56 to which a bearing member 20 is adapted to be held as particularly illustrated in Figure 5, said straight member 56 being provided with suitably spaced openings 57 through which are inserted the headed members 22 associated with said bearing member 20. This straight member 56 is also provided with an opening 58 to receive the outstanding pin 59 carried by the central portion of the bottom or base face of the bearing member 20.

As illustrated in Figure 5, the saw B is in a position for felling a tree and with the

arms 8 vertically disposed and the bearing member 20 engaged with the shaft 18 is fixed to the straight member 56 comprised in the member 55. It is to be understood that by turning the saw B over it will be caused to cut into a tree from either side. With the saw B in a position illustrated in Figure 5, however, it will not saw the desired undercut. In order to effect this undercut it is only necessary to free the member 55 from the shaft 18 and to drop said shaft 18 over to an angle of substantially 45° as shown in Figure 6; and then affix the bearing member 20 carried by the shaft 18 to the intermediate portion 60 of the substantially U-shaped bracket 61, the free extremities of which bracket being provided with angularly related eyes 62 through which are adapted to be disposed the holding members 63 also engageable with the cross members 3 and 4 at a suitable point thereon at either side of the shaft 6. This bracket 61 holds the saw in requisite position to effect the desired undercut and after this has been completed the shaft 18 or more particularly the bearing member 20 carried thereby is released from the bracket 61 and said bearing member is again affixed to the member 55 which maintains the shaft 18 in substantially a vertical position. After the undercut has been completed the saw is turned over and the cut through the tree finished from the side opposite to the undercut.

In felling a tree the chain or flexible member 49 is disposed therearound and properly tightened thereon to hold the adjacent or forward end of the structure S thereto while the opposite end portion of the structure S is adapted to be supported by a stand A. This stand as particularly illustrated in Figure 10 comprises a member 64 substantially U-shaped in form and the free extremities of the side members 65 thereof adapted to be suitably fixed to the side members 1 of the structure S. Overlying the members 65 are the legs 66, said legs being adapted to be adjusted longitudinally with respect to the side members 65 as the occasions of practice may necessitate and in order to maintain said side members 65 and legs 66 in requisite assembled relation the same are provided with the co-acting guide members 67. Each of the side members 65 is provided with a series of longitudinally spaced openings 68 in which is adapted to be selectively engaged a spring pressed latch 69 carried by the associated leg 66 whereby the leg may be held in desired adjustment with respect to the member 64 as the occasions of practice may necessitate.

In Figure 1, the saw B is shown in a position for use to buck a log but it is to be understood that it can be arranged at either side of the structure S as may be preferred. When used to buck, the structure S is held

against the work by the dogs 40. When so used the bearing member 20 carried by the shaft 18 is attached to a side member 1 of the structure S while the bearing members 20 carried by the extremities of the shaft 10 are fixed to the members 3 and 4.

To further maintain the arms 8 vertically disposed when the saw B is employed in felling a tree, I employ in connection with each of said arms the bracket 70 one end of which being provided with a head 71 with which a bearing member 20 carried by the end portion of a shaft 10 is engaged while the opposite end is provided with an angular foot 72 which is held to either cross member 3 or 4.

The eccentric 25 rotates with the shaft 18 and coacts with the straps 26 to oscillate the guide rods 29 whereby the saw will be similarly oscillated or rocked in order to drag out the saw dust.

In Figure 15 I illustrate another embodiment of my invention which is primarily intended for use in bucking although it can be employed to advantage in felling a tree. As comprised in this form the yoke 11' is mounted directly on the shaft 6' but otherwise the structure is substantially the same as has hereinbefore been set forth of the first embodiment of my invention.

From the foregoing description it is thought that a drag saw constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A saw machine of the class described comprising a supporting structure, a driven shaft carried thereby, a second shaft angularly related to the first named shaft, means for supporting said second named shaft for swinging movement about the first named shaft as an axis, an operative connection between both of the shafts, guiding means carried by the second shaft, a saw head slidably engaged with said guiding means, an operative connection between the saw head and the second shaft, a movable member engaged with the supporting structure for swinging movement about an axis transverse to that of the first named swinging movement, and a bearing carried by said movable member and engageable with the second shaft to hold said second shaft in one position.

2. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the last two named shafts against relative swinging movement, guiding means carried by the second shaft, a saw head slidably engaged with said guiding means, and an operative connection between the saw head and the second shaft.

3. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the first named shafts against relative swinging movement, guiding means carried by the second shaft, a saw head slidably engaged with said guiding means, and an operative connection between the saw head and the second shaft.

4. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the first named shafts against relative swinging movement, means for holding the last two named shafts against relative swinging movement, guiding means carried by the second shaft, a saw head slidably engaged with said guiding means, and an operative connection between the saw head and the second shaft.

5. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the last named shaft in a position disposed transversely of the supporting structure, guiding means carried by the second shaft, a saw head slidably engaged with said guiding means, and an operative connection between the saw head and the second shaft.

6. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the last named shaft vertically disposed, guiding means carried by the second shaft, a saw head slidably engaged with said guiding means, and an operative connection between the saw head and the second shaft.

7. A saw mechanism of the class described comprising a supporting structure, a driven shaft carried thereby, arms freely engaged with said shaft, a second shaft supported by said arms, a yoke freely engaged with the second shaft, a third shaft carried by said yoke and angularly related to the second shaft, a driving connection between the first two shafts, a driving connection between the last two shafts, means for holding the last named shaft on a downwardly disposed incline, guiding means carried by the second shaft, a saw head slidably engaged with said guiding means, and an operative connection between the saw head and the second shaft.

In testimony whereof I hereunto affix my signature.

KENNEY F. MILES.
